HIGH SPEED DISCRIMINATOR WITH A WIDE DYNAMIC RANGE HAVING A WIDE AMBIENT TEMPERATURE RANGE

Fred H. Sawada, Scotia, N.Y., assignor to the United States of America as represented by the United States Atomic Energy Commission

Filed Jan. 21, 1966, Ser. No. 522,326
7 Claims. (Cl. 307—88.5)**ABSTRACT OF THE DISCLOSURE**

A pulse discriminator circuit having an output pulse with the same shape and amplitude regardless of the input shape and amplitude. The input pulses are fed via a differentiating network into a first amplifier, through an automatic voltage stabilized back-biased coarse discriminator, into a second amplifier, then into a current stabilized tunnel diode fine discriminator and subsequently into a third amplifier stage.

The invention described herein was made in the course of, or under, a contract with the U.S. Atomic Energy Commission.

This invention relates to electronic pulse circuitry subjected to a wide ambient temperature range, and more particularly to an amplitude sensitive pulse discriminator with a wide dynamic range for eliminating short duration random high frequency input pulses having an amplitude below a pre-set minimum.

Many different pulse height discriminator circuits have been developed for various purposes for radiation detection and for other electronic systems. In the field of nuclear physics, the requirements for rapidity at which the detection and counting of nuclear particles is constantly increasing. Since many forms of counters require pulse discriminators to select desired counts from an input signal having an amplitude that may vary over a wide range from extraneous signals, a circuit is needed which is capable of handling very rapidly occurring sequential pulses having a very narrow width with a minimum delay time within the discriminator. A circuit further is needed having a digital type of output pulse having the same shape and amplitude regardless of the input pulse shape and amplitude, for this relaxes the dynamic range requirements of the subsequent electronic circuitry.

In many scientific instruments, weak positive or negative ion currents must be detected and measured. For example, multistage mass spectrometers may be used to detect and measure ion currents produced by rare isotopes wherein the ion currents typically are 10^{-13} amperes for the larger and 10^{-19} amperes or less for the smaller of two isotopes. Secondary emission electron multipliers have been used for the detection of single particles such as ions because an electron multiplier possesses high gain and good signal to noise ratio. In operation an electron multiplier converts an ion beam into a highly amplified current of electron pulses which can be measured either as a DC current or by pulse counting. Accordingly, it is essential that the dynamic range of the electron multiplier and pulse counting system be 10⁸:1 or greater. A multi-stage electron multiplier which meets this requirement is disclosed in S.N. 441,392 filed Mar. 19, 1965. The present invention with its high dynamic range of 20,000:1 is particularly suitable for use in conjunction with the above described electron multiplier. Known discriminator circuitry with a dynamic range of 100:1 have been found to be unsatisfactory in certain applications.

It is known to employ in electronic pulse circuitry the unique operating characteristics of tunnel diodes and back

2

biased diodes as high speed discriminators to eliminate input pulses having an amplitude below a pre-set minimum. However, the pre-set operating point is subject to change due to changes in the ambient temperature of the device. To prevent triggering of the discriminator which has its operating characteristics altered due to changes in the ambient temperature by spurious noise pulses, the quiescent operating points of the non-compensated devices must be shifted which results in higher counting losses and increases in switching times.

Accordingly, it is an object of the present invention to provide a circuit for maintaining precise control of the threshold of a high speed discriminator with a wide dynamic range under varying ambient temperature conditions.

It is another object to provide a discriminator having a dynamic range of 20,000:1 with an input sensitivity of 1 mv. to 10 volts.

It is another object to provide a circuit for stabilizing the bias point of a tunnel diode when the peak current decreased from a pre-set operating point as a result of large change in the ambient temperature to prevent triggering of the tunnel diode by spurious noise pulses so as to prevent counting losses.

It is another object to provide a circuit to provide for the precise control of a back biased diode discriminator to compensate for the large shift in the forward voltage of the diode as a result of changes in the ambient temperature of the diode so as to prevent counting losses.

It is another object to provide a tunnel diode circuit which has a fast switching time even when subjected to large ambient temperature changes in that the diode can switch more rapidly into the high voltage, low current region due to the higher bias setting of the pre-set operating point.

It is another object to provide for the precise setting of the operating point of a tunnel diode automatically in accordance with changes in diodes operating characteristics due to temperature changes, whereas the conventional method of bias setting by a voltage dividing network changes the output pulse width of the tunnel diode for each bias setting.

It is another object to provide a discriminator having an output pulse with the same shape and amplitude regardless of the input pulse shape and amplitude.

It is another object to provide a temperature sensitive circuit for a tunnel diode so that the tunnel diode's quiescent operating point maintains a more nearly constant relation to the peak current over a wide range of operating temperatures.

The present invention is a discriminator which eliminates input pulses below a preselected amplitude and provides uniform output pulses for input pulses having a range of values between .5 millivolts and 10 volts amplitude. The input pulses as for example from an electron multiplier are fed via a differentiating network in a common emitter transistor amplifier operating near saturation. The amplified positive output pulse of the amplifier is next fed to an automatic voltage stabilized back biased diode coarse discriminator. The positive output of the coarse discriminator is further amplified before being fed into an automatic current stabilized tunnel diode fine discriminator. The positive output of the fine discriminator is further amplified to provide a constant amplitude pulse to a counter or recorder for all input pulses that exceed a preselected amplitude.

The invention will be clearly understood by reference to the accompanying 9 sheets of drawings wherein:

FIGURE 1 is a block diagram of a high speed discriminator circuit with a wide dynamic range having

wide ambient temperature range in accordance with the present invention.

FIGURE 2 is a detailed schematic diagram of the circuitry of the present invention as set forth in the block diagram of FIGURE 1.

FIGURE 7 is a diagram of the characteristics of a tunnel diode, shown to assist in an understanding of the invention.

FIGURE 8 is a diagram of the output pulse of a tunnel diode, shown to assist in an understanding of the invention.

FIGURE 9 is a diagram of the peak current of a tunnel diode with respect to changes in the ambient temperature, shown to assist in an understanding of the invention.

Referring now to FIGURE 1, there is illustrated in block diagram an embodiment of a high speed discriminator circuit with a wide dynamic range having a wide ambient temperature range. High frequency input pulses 0 having an amplitude varying from .5 millivolt to 10 volts with a frequency as high as 100 megacycle are applied to input terminal 11 for providing an output terminal 12 a digital type of output pulse 13 having the same shape and amplitude regardless of the input pulse shape and amplitude. Input pulses 10 are passed through differentiating network comprised of capacitor 14 and resistor 15 which differentiates input pulse 10 to provide a negative and positive pulse as represented by reference figure 16 corresponding to the leading and trailing edge of the input pulse to a first amplifier 17 which results in positive output pulse 18. Output pulse 8 is applied to the input of a back biased PN junction diode coarse discriminator circuit 19 which eliminates input pulses below a certain pre-set level and passes pulses above this level as designated by reference figure 20.

To prevent shifting of the pre-set bias point of the back biased diode circuit as a result of changes in the forward voltage of the diode caused by changes in the ambient temperature, the pre-set bias level of the back biased diode discriminator is controlled by the automatic voltage stabilizing circuit 21.

The output 20 of the automatically stabilized discriminator 19 is connected to a second amplifier 22 so that amplified output pulse 23 is applied to a tunnel diode circuit 24 which eliminates input pulses below a certain pre-set level and passes above this level an output pulse 25 having the same shape and amplitude, regardless of the input pulse 10 shape or amplitude.

An inherent characteristic of the tunnel diode is that the peak current decreases with rises in the ambient temperature. This change is generally toward the negative direction from 25° C. ambient. Therefore, to offset this shift of peak current an automatic current stabilizer 6 is connected to the tunnel diode discriminator circuit 24.

The output pulse 25 of tunnel diode discriminator circuit 24 is further amplified by means of the third amplifier 27 to provide an output pulse 13 at output terminal 12.

Referring now to FIGURE 2, there is illustrated a detailed schematic diagram of the present invention as set forth in the block diagram of FIGURE 1 of the high speed discriminator with a wide dynamic range having a wide ambient temperature range.

Negative pulse 10 is applied to input terminal 11 across which is shunted input terminating resistor 28 to ground. Terminal 11 is connected to a differentiating network comprised of capacitor 29 and a resistor 30.

Resistor 30 is shunted across the capacitor's output 31 and ground so that input pulse 10 is differentiated to provide a negative and a positive pulse corresponding to the leading and trailing edge of the input pulse as may be seen by the waveform represented by reference figure 16. The output of the differentiating network formed by the junction of output 31 of capacitor 29 and resistor 30 is connected to the first amplifier 17 by conductor 32.

First amplifier

The output pulse 16 of the differentiating network is applied to the base 33 of transistor 34 of first amplifier 17. Transistor 34 is biased by connecting its base 33 to a positive voltage terminal 35 by serially connected resistor 36 and inductor 37. The emitter 38 of transistor 34 is connected via resistor 39 to ground. Capacitor 40 is shunted across resistor 39 so that the resistor 39 and capacitor 40 prevent degeneration. The collector 41 of transistor 34 is connected to the positive voltage terminal 35 by the series circuit of inductor 42 and resistor 43. A DC blocking capacitor 44 connected to the collector 41 of transistor 34 constitutes the output connection for the first amplifier 17.

In operation input pulse 10 is applied to the differentiating network comprised of capacitor 29 and resistor 30 so that a differentiating pulse with both a negative and positive peak designated by reference figure 16 will be applied to base 33 of NPN transistor 34 of amplifier 17. Transistor 34 is biased near saturation so that only the negative peak will be amplified, inverted in polarity, and passed through capacitor 44 as designated by reference figure 18.

The amplification of the negative input pulses and the clipping of the positive input pulses may be more clearly understood by reference to FIGURE 3 which is a diagram of the characteristics of a common-emitter transistor amplifier 17.

In FIGURE 3, there is shown the output characteristic curves of a common emitter transistor amplifier 17 with the collector current plotted on the ordinate axis and the collector voltage plotted on the abscissa axis for various values of base current. To establish the load line on the characteristic curves of FIGURE 3, a point respectively on the abscissa and ordinate axis must be located. When the collector current is zero the total collector supply voltage equals the collector voltage and is designated as reference point 46 on the abscissa of the plot in FIGURE 3. When the voltage on the collector is zero, then the total collector supply voltage is dropped across the load resistor 43 for amplifier 17 and the collector current may be determined and designated as point 47 on the ordinate of the plot in FIGURE 3. Connecting points 46 and 47 with a straight line establishes the load line 48. From the characteristic curves with load line of FIGURE 3, distinct operating regions may be observed for a common emitter amplifier. Reference figure 49 designates the saturation region. In this region the emitter and collector are biased in the forward direction and the input impedance at this operating point will be very low. This is also the high current region. Reference figure 50 designates the normal operating region for a transistor, and in this region the emitter is forward biased and the collector is reverse biased. By operating transistor 34 near saturation at quiescent point 51 on load line 48, only the negative input peak will be amplified and the positive input peak clipped because only the negative portion of input pulse 52 results in an output across the load as output voltage pulse 18 and output current pulse 54. By further operating amplifier 17 near saturation, the maximum swing on the load line may be obtained for large negative input signals with a minimum of distortion.

One of the problems with transistorized circuitry is the inherent capacitive reactance of transistors at high frequencies. This reactance varies with frequency and

may result in network instability or oscillation which is due to the internal feedback through the collector to base capacitance. In addition this reactance causes a change in the input and output impedance levels which may decrease as much as two to one at frequencies greater than 100 megacycles thus destroying linearity and amplifying ability of the network. Accordingly, the object of inserting inductors 37 and 42 in the base and collector circuits of amplifier 17 is to partially neutralize the input and output capacitance of transistor 34 and to assure an adequate impedance level to maintain an adequate amplifier output signal level.

*Back biased diode coarse discriminator
and automatic voltage stabilizer*

The output pulse 18 from the first amplifier 17 is fed through blocking capacitor 44 to the back biased diode coarse discriminator 19 by impressing pulse 18 on the junction 53 formed by resistors 55 and 56. Potentiometer 55, disposed between junction 53 and voltage source 35, and resistor 56 disposed between junction 53 and ground constitutes the variable voltage divider, biasing network for back biased diode 57. The side of diode 57 opposite junction 53 is connected to blocking capacitor 58 having an electrical conductor 59 which constitutes the output for coarse discriminator 19.

Automatic voltage stabilizer 21 is comprised of a resistor 60 connected from the junction between back biased diode 57 and capacitor 58 to a tap on variable resistor 61. One end of variable resistor 61 is connected to the collector of transistor 162. The end of variable resistor not connected to transistor 162 is connected to junction 62 formed by resistor 63 and sensitor 64 which is thermally coupled to diode 57. The ends of resistors 63 and 64 not connected to junction 62 are grounded. The emitter of transistor 162 is connected to one end of potentiometer 65. The other end of potentiometer 65 not connected to transistor 162 is connected to the junction 66 formed by resistor 67 and sensitor 68 which is thermally coupled to diode 57. The ends of resistor 67 and sensitor 68 not connected to junction 66 are connected to voltage source 35. A reversed-biased or zener diode 69 is connected across source 35 and the base of transistor 162 for voltage stabilization purposes. Resistor 70 is connected to ground from the base of transistor 162 to complete the automatic voltage stabilizer 21.

The thermal coupling of sensitors 64 and 68 to back biased diode 57 may be more clearly understood by referring to FIGURE 4. To maintain a more precise thermal coupling so as to detect the rise in temperature of back biased PN junction diode 57, sensitors 64 and 68 are attached thereto by wrapping "Mylar," a polyester film, tape 71 around the sensitors and the diode.

In the operation of back biased diode coarse discriminator 19, a pulse 18 is applied to PN junction diode 57. A semiconductor diode, such as diode 57 is made of two materials, a donor which is an "N" material with electrons as the majority carrier as designated by reference figure 72 in FIGURE 2, and a "P" material with "holes" as the majority carrier as designated in reference figure 73 in FIGURE 2. Within a single crystal the two materials will cause the formation of a PN junction. When a PN junction is formed a small current will flow as the result of "holes" crossing the junction and electrons moving in the opposite direction. Because of electrical equilibrium requirements, this migration will finally cease and there will exist within the junction region a barrier. The "P" side becomes electrically more negative while the "N" side becomes more positive. This potential difference or internal potential barrier which exists at the junction or interface now opposes any movement of carriers. The carriers both "holes" and electrons are influenced by this potential barrier and both carriers tend to shy away from this area. Therefore, in the vicinity of this junction there is a depletion of both majority

carriers, i.e. electrons and holes. Thus the region is defined as the depletion region, and an electric field exists this region. In the region there still exists a few donor and acceptor atoms carrying a negative or positive charge. These atoms are bound in the lattice structure of the crystal and are influenced by the electric field that exists in this region. If a small forward potential is applied at the "P" side of the PN junction so as to lower or nullify this potential barrier, a flow of current will occur as a result of lowering of the potential barrier. If, however, a small negative voltage is applied at the "P" side of the junction, instead of a positive potential the potential barrier of the PN junction is increased by the addition of the negative bias resulting in an increased resistance across the PN junction.

By adjusting the reverse bias on the "P" side 73 of PN junction diode 57 with respect to "N" side 72 means of the voltage dividing network comprised of variable resistor 55 and resistor 56, the threshold of back biased coarse discriminator 19 is established. Thus, if an incoming pulse such as designated by reference figure 74 is of insufficient value to lower the potential barrier of the back biased diode or the pulse will not pass through the diode discriminator. If the input signal is of sufficient value to overcome the internal potential, the diode is effect forward biased and current flow will result.

This may be seen by referring to the static characteristic curve of FIGURE 5 for a typical silicon PN junction diode at an ambient temperature of 25° C. having the diode current plotted on the ordinate axis and the diode's forward voltage plotted on the abscissa axis. Reference figure 74 designates the threshold voltage P_0 for a PN junction diode or the point at which the diode is a conducting or "on" state. Accordingly, any input signal greater in amplitude than the threshold voltage P_0 as represented by figure 74 will pass through the diode and any signal less than P_0 will not pass through. By biasing the diode or applying a negative voltage to the "P" side with respect to the "N" side of the diode or certain input signals will have sufficient amplitude to exceed the threshold 74 so as to pass through the diode.

However, a problem arises in that point 74 is temperature sensitive. An inherent characteristic of PN diodes is that the forward voltage decreases with rises in ambient temperature. Typically this change is about $mv./^{\circ}C.$. Therefore, for a 25° C. rise in temperature the forward voltage of a diode will be decreased by $mv.$ This change in the characteristic curve for a diode for various temperature rises is shown in FIGURE 6. This large shift in the forward voltage effects the pre-bias level so that close control of the threshold of a back biased diode discriminator is extremely difficult to maintain, resulting in an input signal of a lower amplitude than desired to pass through the diode. Assuming that the voltage dividing network comprised of variable resistor 55 and resistor 56 were adjusted to set bias point 75, then any positive voltage greater than the difference between the threshold point 74 and the bias point 75 would pass through the diode. However, if the diode temperature increases to 50° C., the threshold is shifted to 74'. Therefore, any input signals greater than the difference between threshold 74' and bias point 75 would pass through the diode. In that the difference between 74 and 75 is greater than the difference between 74' and 75, the diode discriminator becomes temperature sensitive and passes input pulses of lower amplitude as the temperature increases. To offset this loss in the forward voltage, additional reverse bias must be supplied at the N junction to shift the bias point to 75' so that the difference between 74' and 75' is the same as the difference between 74 and 75 so that only signals of a predetermined amplitude will pass through the diode irrespective of changes in the ambient temperature of the diode.

The automatic compensating or nullifying of the diode shift (decreases in this embodiment) in the forward voltage

e may be understood more clearly by referring to FIGURE 2. The current through resistance 61 is controlled by potentiometer 65. Since 61 is a variable resistor, the as in the "N" side of the PN junction diode 57 can be carried by either potentiometer 65 which changes the current through resistor 61 or maintaining a constant current fixing resistor 65 and changing the resistance of resistor . In the specific embodiment, sensistor 64 has a positive efficient of resistance of 0.7 ohm/° C. At ambient temperature, sensistor 64 has a nominal value of 200 ohms. t a temperature rise of 25° C., the change in sensistor would be 200 ohms+.7 ohm/° C.×25° C., or a total 217.5 ohms. The equivalent resistance of resistors 63 and 64 at ambient temperature is 100 ohms. At a 25° C. rise in temperature from 25° C. ambient, this equivalent resistance changes to 104 ohms, at net change of 4 ohms. t a 50° C. rise in temperature, the equivalent resistance is 108 ohms. Thus, the total change of the equivalent resistance of the parallel combination of resistors 63 and 64 is 8 ohms. As it was stated above, each degree C. rise in the ambient temperature changes the forward voltage of the PN junction diode by 2 mv. Therefore, at 5° C. rise from an ambient temperature of 25° C., the range would be 50 mv.; and at a 50° C. rise from ambient this change would be 100 mv. Thus, the total shift loss of forward voltage is 100 mv. for a temperature excursion of 50° C. from an ambient of 25° C. To avoid lse triggering of the back biased diode caused by the ss of forward voltage due to changes in temperature, compensation is required to offset this loss in the forward voltage. In that the total change of the equivalent resistance for the parallel network comprised of resistors 63 and 64 is 8 ohms from an increase in temperature on the ambient of 25° C. to 75° C. and the shift in the forward voltage of diode 57 from ambient to 75° C. is 50 mv., the current through the series parallel network of resistors 63 and 64 should be 12.5 ma. to offset the ss in forward voltage ($i = e/r$, or 100 mv./.8). By calculating the voltage across the parallel network of resistors 63 and 64, it is found that the voltage drop across the network at 25° C. is $e = ir$ or $e = 100 (12.5 \times 10^{-3}) = 1.25$ volts; the drop at 50° C. is $e = 104 (12.5 \times 10^{-3}) = 1.30$ volts and the drop at 75° C. is 108 ($12.5 \times 10^{-3} = 1.35$ volts).

As was pointed out above, at 75° C. the change in the forward voltage for diode 57 is 100 mv. (50° C.×2 mv./ C.). To offset this loss in forward voltage an additional reverse bias must be applied at N junction 72 of diode 7 to make up for this loss. By subtracting the voltage drop across the parallel combination of resistors 63 and 64 at an ambient of 25° C. which is 1.25 volts from 5° C. ambient which is 1.35 volts, it may be seen that 1 volt or 100 mv. is added to "N" junction 72. Therefore, the PN junction loss of forward voltage is compensated by the additional reverse bias voltage of 100 mv. when the equivalent resistance of resistors 63 and 64 increased from 100 to 108 ohms.

The current of 12.5 ma. is set by potentiometer 65 and the threshold bias for diode discriminator 57 is set by sensistor 61. The value of resistor 65 may be calculated as follows. If the beta of the transistor is high (transport ictor, see Middlebrook, An Introduction to Junction transistor Theory, 145 (1957)), then the collector I_c may be approximated by the emitter current I_e . Therefore:

$$I_e = I_c \frac{V_z - V_{be}}{R_v + R_t} \quad (1)$$

Here:

z = zener diode 69 voltage rating which is 6.3 volts for Type 1N827

be =internal potential shift of a PN junction diode due to the rise in ambient temperature which is .6 volt at 25° C. and changes by 2 mv./° C.

v =resistor 65

R_t =resistor 67 times resistor 68 divided by the sum of resistors 67 and 68. $(R_{67} \times R_{68}) / (R_{67} + R_{68})$

at an ambient temperature of 25° C.:

$$5 \quad 12.5 \times 10^{-3} = \frac{6.3 - .6}{R_v + 100} \quad (1)$$

solving for R_v

$$R_v = R_{65} = 356 \text{ ohms}$$

It may be seen that at 50° C., I_c remains a constant by substituting in Equation 1 the following:

$$10 \quad I_c = I_e = \frac{6.3 - (.6 - (25^\circ \text{C.} \times 2 \text{ mv./}^\circ \text{C.}))}{356 + 104} = 12.5 \times 10^{-3} \quad (1)$$

15 Accordingly, the precise control of coarse back biased discriminator 19 is maintained in face of varying temperature changes of the circuit itself.

Second amplifier

20 The output pulse as represented by reference figure 20 from the back biased coarse discriminator 19 is applied to the second amplifier 22 via electrical conductor 59 as may be seen in FIGURE 2. Electrical conductor 59 is connected to the emitter of a NPN transistor 76 having a resistor 77 connected from the emitter to ground. The base of transistor 76 is connected to junction 78 formed by grounded resistor 79 and grounded capacitor 80. The base of transistor 76 is connected to positive voltage terminal 81 of 8 volts by the serially connected inductor 82 and resistor 83. The collector of transistor 76 is connected to the positive voltage terminal 81 by the serially connected inductor 84 and resistor 85. A DC blocking capacitor 86 connects the collector of transistor 76 to the emitter of a NPN transistor 87 having a resistor 88 connected from the emitter to ground. The base of transistor 87 is connected to junction 89 formed by grounded resistor 90 and grounded capacitor 91. The base of transistor 87 is connected to the positive voltage terminal 81 by serially connected inductor 92 and resistor 93. The collector of transistor 87 is connected to the positive voltage terminal 81 by serially connected inductor 94 and resistor 95. Electrical conductor 96 connected to the collector of transistor 87 constitutes the output for second amplifier 22.

45 In operation input pulse 20 derived from the back biased coarse discriminator 19 is applied to the input of second amplifier 22. Second amplifier 22 consists of two NPN transistors 76 and 87 in a common base amplifier configuration. The amplifier input 20 appears at the output 96 of second amplifier 22 as an amplified output pulse 23.

50 As in the case of the first amplifier 17, inductors are inserted in the circuits of transistors 76 and 87 to partially neutralize the output capacitance of the transistors and to assure an adequate impedance level at the operating frequency so as to maintain an adequate amplifier output signal level.

Tunnel diode fine discriminator and automatic current stabilizer

60 The positive output pulse 23 at the collector of transistor 87 is coupled by means of electrical conductor 96, capacitor 97, and resistor 98 to tunnel diode 99 at junction 100. The collector of PNP transistor 101 is connected to junction 100 by serially connected resistor 102 and inductor 103. The collector of transistor 101 is bypassed to ground by capacitor 104. The base of transistor 101 is connected to ground by means of resistor 105. A reversed-biased or zener diode 106 is connected across the positive voltage source 81 and the base of transistor 101 for voltage stabilization purposes. A potentiometer 107 is connected between the emitter of transistor 101 and the positive voltage source 81 by means of sensistor 108 which is thermally coupled to tunnel diode 99. A serially connected capacitor 109 and resistor 114 con-

nected to junction 100 constitutes the output for tunnel diode fine discriminator 24.

The thermal coupling of sensitor 108 to tunnel diode 99 having a positive connection 110 and a ground connection 111 may be more clearly understood by referring to FIGURE 6. To maintain a more precise thermal coupling, sensitor 108 held by mounting 112 is spring loaded by means of spring 113 to forcibly engaging sensitor 108 and ground connection 111 of diode 99 so as to detect the rise in temperature of tunnel diode 99.

In the operation of the tunnel diode fine discriminator 24, the positive pulse 23 from the collector of transistor 87 fires the tunnel diode 99 to provide an output pulse 25 through capacitor 109 and resistor 114.

Reference is made to FIGURE 7 wherein there is shown a plot of the current flowing through the tunnel diode 99 versus the voltage thereacross, and to FIGURE 8 which shows the output pulse of the tunnel diode. The tunnel diode's characteristics are represented by the curve 115. As the voltage increases to some value V_p , the current through the tunnel diode will increase to a peak value I_p . The point on the characteristic curve 115 at which these values occur is designated by reference number 116. As the voltage increases beyond the value V_p , the current through the tunnel diode decreases indicating that the tunnel diode has a negative characteristic. The decrease in current continues with increases in voltage until the voltage reaches the value V_v . The point on the characteristic curve 115 at which the lowest value of current flows at voltage V_v is designated by reference number 117. Thereafter, the current through the tunnel diode will increase with increasing voltage to a high voltage V_f which is represented on the characteristic curve 115 by reference number 118. Between the two points 116 and 117 on characteristic curve 115, there is a region in which the tunnel diode exhibits a negative resistance characteristic. This is not a stable region, and a tunnel diode will try to go either to a potential lower than V_p or higher than V_v , both of which would be stable states.

Tunnel diode 99 is biased in the forward direction by potentiometer 107 to locate the quiescent operating point 119 on the positive slope of the low voltage-high current region of characteristic curve 115. The peak of the positive pulse 23 from second amplifier 22 will switch the tunnel diode to the high voltage state 118 as may be seen in FIGURE 7 to produce the leading edge of output pulse 120 as may be seen in FIGURE 8. The current in inductor 103 will decrease exponentially from its value at 118 until it reaches the valley current I_v at which time the tunnel diode will switch back to its low voltage state. The switching time from point 116 to 118 on curve 115 of FIGURE 7 is the rise time which is also seen for output pulse 120 in FIGURE 8. The time interval between points 118 and 117 is the pulse duration. The time interval between points 117 and point 121 is the fall time of the output pulse. Point 121 relates to the point on curve 115 corresponding to low voltage value for I_v on the low voltage portion of curve 115. The recovery time of the output pulse is that interval of time between 121 and the quiescent operating point 119 as shown in FIGURES 7 and 8. Accordingly, the total time of the output pulse is less than ten nanoseconds.

An inherent characteristic of the tunnel diode is that the peak current 116 decreases with rises in the ambient temperature and is generally toward the negative direction from 25° C. ambient as may be seen in FIGURE 9. The lowering of the peak current may be noted by observing in FIGURE 7 the characteristic curve 115' for tunnel diode 99 at 50° C. which is represented by dashed lines relative to characteristic curve 115 at 25° C. The original quiescent bias point 119 now exceeds the threshold 116' for characteristic curve 115'. This excess bias will force the tunnel diode to switch to the high voltage region without the application of an input signal.

An automatic temperature compensating current source designated by reference figure 26 is used to offset the change in the peak current and is shown schematically in FIGURE 2. Source 81 controls the emitter current of transistor 101 by the voltage V_1 which is applied across the series resistance 108 and 107. If the beta of transistor 101 is high, then I_c (collector current) may be approximated as I_e (emitter current). The emitter current is determined by the applied voltage across resistors 107 and 108. Therefore:

$$I_e = I_c = I_{td} = \frac{V_z - V_{eb}}{R_s + R_v} \quad (2)$$

Where:

I_e =emitter current

I_c =collector current

I_{td} =tunnel diode current

V_{eb} =base to emitter voltage (0.6 volt for silicon transistor at an ambient temperature of 25° C., this voltage decreases linearly 2 mv./° C.)

V_z =zener voltage (5.6 volts in this embodiment)

V_1 =applied voltage

R_s =sensitor 108 (500 ohms with a positive coefficient of resistance of 0.7 ohm/° C.)

R_v =resistor 107 (potentiometer with a resistance of 0 to 5 ohms)

Letting:

30 $V_z=5.6$ volts

$V_{eb}=0.6$ volt

$R_s=500$ at ambient temperature of 25° C.

$R_v=0$ ohm (shorted out)

35 Substituting the above in Equation 2, the tunnel diode bias is:

$$I_{td} = \frac{V_z - V_{eb}}{R_s + R_v} = \frac{5.6 - .6}{500} = 10 \text{ ma.} \quad (3)$$

From the analysis of the curve of FIGURE 9, which 45 is a diagram of the peak current of a tunnel diode with respect to changes in the ambient temperature, the peak current through the tunnel diode at 25° C. ambient is 1 ma. as compared to the peak tunnel diode current shift to 9.8 ma. at 50° C. as represented by reference point 50 116' in FIGURE 7. Thus, the shift in peak current is 9.8 ma. or 2%. If the operating point 119 is set at 9.9 ma. by resistor 107, the tunnel diode will switch to the high voltage-low current region without the application of an input signal as the peak current shifts from 10 ma. to 9.8 as a result of a change in the tunnel diode's temperature from 25° C. to 50° C.

In the specific embodiment of the automatic current stabilizer 26 will lower the quiescent operating point 119' to prevent the tunnel diode from switching to the high voltage-low current region without the application of an input signal as the tunnel diode's temperature changes from 25° C. to 50° C. In the specific embodiment the peak bias current is 10 ma. for a type 1N385 tunnel diode. Since sensitor 108 has a positive coefficient of 0.7 ohm per degree C., then a 25° C. rise from the ambient temperature of 25° C. will result in a change in I_e of 500 ohms $+0.7 \text{ ohm/}^\circ \text{C.} \times 25^\circ \text{ C.}$ or $R_s=517$ ohms.

At a change in temperature of 25° C. from ambient the change in bias current from the automatic current stabilizer 26 can be determined from Equation 2. Where:

70 $V_z=5.6$ volts

$V_{eb}=0.6$ volt

75 $R_s=0$

accordingly:

$$I_{td} = \frac{5.6 - .6}{517.5}$$

$$I_{td} = 9.67 \text{ ma.} \quad (2'')$$

If the base to emitter voltage shift for a silicon transistor is considered then the change in bias current from current stabilizer 26 would be:

$$I_{td} = \frac{5.6 - (0.6 - 2^\circ \text{C.} \times 0.002 \text{ volt}/^\circ \text{C.})}{517.5}$$

$$I_{td} = 9.75 \text{ ma.} \quad (2''')$$

Thus, by comparing the results of the Equation 2' for the current through the tunnel diode at 25° C. which is 0 ma. to the current through the tunnel diode at 50° C. which is 9.75 ma. (see 2'''), the bias current change by automatic current stabilizer circuit shifts the tunnel diode 9 peak current 2.5% for a 25° C. rise from the ambient temperature. The temperature compensating network 108 current stabilizer 26 will lower the quiescent point 119' to 9.75 ma. as may be seen in FIGURE 7. This new threshold point will still maintain nearly the same degree of input sensitivity at 50° C. as was the case at 25° C. Thus, with the automatic current stabilizer 26, stability of an operating point with respect to the characteristic curve of a tunnel diode is maintained at wide ranges of operating temperatures so that the quiescent operating point maintains a more nearly constant relationship to the peak current.

Third amplifier

The output pulse, as represented by reference figure 25, from the tunnel diode fine discriminator 24 is applied to the third amplifier 27 via electrical conductor 122. As may be seen in FIGURE 2, electrical conductor 122 is connected to the emitter of a NPN transistor 123 having a resistor 124 connected from the emitter to ground. The base of transistor 123 is connected to junction 125 formed by grounded resistor 126 and grounded capacitor 127. The base of transistor 123 is connected to positive voltage terminal 81 by the serially connected choke 128 and resistor 129. The collector of transistor 123 is connected to the positive voltage terminal 1 by the serially connected choke 130 and resistor 131. DC blocking capacitor 132 connects the collector of transistor 123 to the emitter of a NPN transistor 133 having a resistor 134 connected from the emitter to ground. The base of transistor 133 is connected to junction 135 formed by grounded resistor 136 and grounded capacitor 137. The base of transistor 133 is connected to positive voltage source 81 by serially connected choke 138 and resistor 139. The collector of transistor 133 is connected to the positive voltage terminal 81 by serially connected choke 140 and resistor 141. The collector of transistor 133 is connected to the output terminal 12 of the discriminator-amplifier by a DC blocking capacitor 142. Terminating resistor 143 is connected from the output terminal 12 to ground for matching purposes.

As in the case of the first amplifier 17, the inductors are inserted in the circuits for transistors 123 and 133 to partially neutralize the output capacitance of the transistors and to assure an adequate impedance level at the operating frequency so as to maintain an adequate amplifier output signal at terminal 12.

In operation, input pulse 25 derived from the tunnel diode fine discriminator 24 is applied to the input of third amplifier 27 consisting of two NPN transistors 123 and 133 in a common base amplifier configuration. The input pulse 25 to the third amplifier appears at the output terminal 12 as amplified output pulse 13.

In one embodiment of the invention the following circuit parameters were employed. The values are given for purposes of clearly setting forth the invention and are not intended to be construed as limiting the invention.

- Resistor 28—51 ohms
- Capacitor 29—50 picofarads
- Resistor 30—1.2K
- Transistor 34—Type 2N2865
- 5 Resistor 36—2.7K
- Inductor 37—0.3 microhenry
- Resistor 39—68 ohms
- Capacitor 40—600 picofarads
- Inductor 42—0.3 microhenry
- Resistor 43—300 ohms
- Capacitor 44—1 microfarad
- Resistor 55—100K ohms
- Resistor 56—4.7K ohms
- Diode 57—Type 700D
- 15 Capacitor 58—1 microfarad
- Resistor 60—5.6K ohms
- Resistor 61—1K ohm
- Transistor 62—Type 2N1132
- Resistor 63—200 ohms
- 20 Sensistor 64—200 ohms
- Resistor 65—10K ohms
- Resistor 67—200 ohms
- Sensistor 68—200 ohms
- Zener Diode 69—Type 1N827
- 25 Resistor 70—1.8K ohms
- Transistor 76—2N2865
- Resistor 77—75 ohms
- Resistor 79—82 ohms
- Capacitor 80—500 picofarads
- 30 Inductor 82—0.3 microhenry
- Resistor 83—300 ohms
- Inductor 84—0.3 microhenry
- Resistor 85—270 ohms
- Capacitor 86—.01 microfarad
- 35 Transistor 87—Type 2N2865
- Resistor 88—75 ohms
- Resistor 90—82 ohms
- Capacitor 91—500 picofarads
- Inductor 92—0.3 microhenry
- 40 Resistor 93—300 ohms
- Inductor 94—0.3 microhenry
- Resistor 95—270 ohms
- Capacitor 97—25 picofarads
- Resistor 98—22 ohms
- 45 Tunnel Diode 99—Type 1N3858
- Transistor 101—Type 2N1132
- Resistor 102—20 ohms
- Inductor 103—0.15 microhenry
- Capacitor 104—.01 microfarad
- 50 Resistor 105—180 ohms
- Zener Diode 106—Type 1N827
- Resistor 107—5K ohms
- Sensistor 108—500 ohms
- Capacitor 109—.01 microfarad
- 55 Resistor 114—68 ohms
- Transistor 123—Type 2N2865
- Resistor 124—75 ohms
- Resistor 126—82 ohms
- Capacitor 127—500 picofarads
- 60 Inductor 128—0.3 microhenry
- Resistor 129—300 ohms
- Inductor 130—0.3 microhenry
- Resistor 131—220 ohms
- Capacitor 132—.01 microfarad
- 65 Transistor 133—2N2865
- Resistor 134—75 ohms
- Resistor 136—82 ohms
- Capacitor 137—500 picofarads
- Inductor 138—0.3 microhenry
- 70 Resistor 139—300 ohms
- Inductor 140—0.3 microhenry
- Resistor 141—220 ohms
- Capacitor 142—.01 microfarad
- 75 Resistor 143—51 ohms

It will be understood that various changes in the details, steps and arrangement of parts which have been described and illustrated in order to explain the nature of the invention may be made by those skilled in the art within the principle and scope of the invention as expressed in the appended claims.

I claim:

1. A high frequency pulse amplifier discriminator for providing a constant amplitude output pulse for all input pulses within a desired wide range, comprising:

an electrical source;

an input circuit for receiving said input pulses;

differentiating circuit means having an input and an output, for differentiating said input pulse to provide a negative and positive pulse, said input being connected to said input circuit;

a first transistor amplifier having an input and an output, said input connected to the output of said differentiating circuit means, said amplifier biased near saturation for amplifying said negative pulse and 20 clipping said positive pulse;

a diode discriminator having an input, and an output said input connected to the output of said first amplifier;

means for back biasing said diode discriminator at a 25 predetermined threshold whereby pulses are provided in response to input pulses from said first amplifier which exceed a predetermined value;

automatic voltage stabilizer means thermally coupled to said diode for controlling the threshold of said diode during the shift of the diode's forward voltage caused by changes in temperature of said diode;

a second amplifier having an input and output, the input being connected to said output of said diode discriminator;

a tunnel diode discriminator connected to the output of said second amplifier;

means for biasing said tunnel diode at a predetermined threshold whereby pulses are provided in response to input pulses from said second amplifier which exceed 40 a predetermined value;

automatic current stabilizing means thermally coupled to said tunnel diode for controlling the threshold of said tunnel diode during the shift of the diode's peak current caused by changes in temperature of said 45 tunnel diode;

a third amplifier having an input and an output terminal, said input connected to the said tunnel diode.

2. A high frequency pulse amplifier discriminator according to claim 1 wherein the second amplifier is a common base transistor configuration.

3. A high frequency pulse amplifier discriminator according to claim 1 wherein the third amplifier is a common base transistor configuration.

4. A high frequency pulse amplifier discriminator according to claim 1 wherein the automatic voltage stabilizer means includes:

a transistor having a collector, emitter and a base;

a sensor having a first and second terminal, thermally coupled to said diode, said first terminal being 60 grounded;

a first resistor, having a first and second terminal, said first terminal being grounded, said second terminal connected to the second terminal of said sensor so as to define a first junction;

a variable resistor having a tap connection, one end of said variable resistor being connected to the said first junction between said sensor and first resistor, the other end of said variable resistor being connected to the collector of said transistor;

a second resistor connected between the tap of said variable resistor and said output of said diode;

a zener diode connected between the said source and the base of said transistor;

a third resistor connected between the base of the transistor and ground;

a second sensor having a first and second terminal, said first terminal being connected to the said source;

a fourth resistor having a first and second terminal, said first terminal connected to said source, said second terminal connected to the second terminal of said second sensor so as to define a second junction;

a potentiometer connected between the emitter of said transistor and the said second junction.

5. A high frequency pulse amplifier according to claim 1 wherein the automatic current stabilizing means includes:

a transistor having a collector, emitter and a base; a sensor having a first and second terminal thermal coupled to said tunnel diode, said first terminal connected to said voltage source;

a potentiometer connected from said emitter of said transistor to said second terminal of said sensor;

a first resistor connected from the base of said transistor to ground;

a zener diode connected between said source and the base of said transistor;

a first capacitor connected from the collector of said transistor to ground;

a second resistor and an inductor serially connected between the collector of said transistor and said tunnel diode.

6. A pulse discriminator:

an input terminal;

an electrical source;

a potentiometer connected between the source of said input terminal;

a first resistor connected between the input terminal and ground;

a diode having an input and an output, said input connected to said input terminal;

an output terminal;

a capacitor connected between the output of said diode and the output terminal;

a transistor, having a collector, emitter and a base connection;

a sensor having a first and second terminal, thermal coupled to said diode, said first terminal being grounded;

a second resistor having a first and second terminal, said first terminal being grounded, said second terminal connected to the second terminal of said sensor so as to define a first junction;

a variable resistor having a tap connection, one end of said variable resistor being connected to the first junction between said sensor and first resistor, the other end of said variable resistor being connected to the collector of said transistor;

a third resistor connected between the tap of said variable resistor and the output of said diode;

a zener diode connected between the said source and the base of said transistor;

a fourth resistor connected between the base of the transistor and ground;

a second sensor having a first and second terminal, said first terminal being connected to the source;

a fifth resistor having a first and second terminal, said first terminal connected to said source, said second terminal connected to the second terminal of said second sensor so as to define a second junction; and a potentiometer connected between the emitter of said transistor and said second junction.

7. A pulse discriminator:

an input terminal;

an electrical source;

a tunnel diode having a first and second terminal, said first terminal connected to the input terminal, said second terminal being grounded;

a transistor having a collector, emitter and base;

- 1 a first resistor and an inductor serially connected between the collector and the input terminal, said inductor being connected to the input terminal;
- 2 a capacitor connected between ground and the collector of the transistor;
- 3 a second resistor connected from the base of the transistor to ground;
- 4 a zener diode connected between the said source and the base of the transistor;
- 5 and a sensor thermally coupled to said tunnel diode, 10 and a potentiometer serially connected between the

emitter and the said electrical source, by means of the sensor.
